Q.S. 2376

Henry Scouermond New York N.Y.

Letter's Patent No. 2376. Dated Aug. 7. 1866.

Design for Work Basket Stand.

The Schedule referred to in this Letter's Patent, and making part of the same.

To all whom it may concern:

Be it known that I, Henry Scouermond of the City, County, and State of New York have invented a new and improved Design for Work Basket Stand, and I do hereby declare that the following is a full, clear, and exact description thereof which will enable those skilled in the art to understand the same, referencing had to the accompanying drawings forming part of this specification (the drawing represents a side view of this invention).

This Design relates to the Stand of a work basket the distinguishing features of which are three columns the upper parts of which support the basket while the lower parts branch off and form the legs on which the stand stands. Under the work basket the columns are ornamented by small baskets secured to their outside and by other baskets secured between said columns the whole being combined so as to form an article of neat and elegant appearance.

A, represents the work basket which is supported by three columns B, the lower ends of which branch off to form the legs C, Under the basket A, and secured to the columns B, are three small baskets D, and two other baskets E, F, are applied between the columns, one about the middle of their height, and one near their bottom ends. V shaped brace G, connects the columns at about the middle of their height and forms an additional ornament for the stand.

Having thus described my invention, I claim as new and desire to secure by Letter's Patent,

The Design for a Work Basket Stand as shown and described witness

Wm. A. Mamaras

W. Hauff.
